UNITED STATES PATENT OFFICE.

GOTTFRIED WIRER, OF PLAINFIELD, NEW JERSEY, ASSIGNOR TO INTERNATIONAL MOTOR COMPANY, OF NEW YORK, N. Y., A CORPORATION OF DELAWARE.

VAPORIZER-TEMPERATURE CONTROL.

Application filed August 15, 1925. Serial No. 50,845.

This invention relates to internal combustion engines adapted particularly for driving pumps on fire apparatus. More particularly the invention relates to such internal combustion engines when provided with what is known as a hot spot where the vaporization of the fuel from the carburetor to the intake manifold is facilitated. It has been the experience when running motors of fire apparatus equipped with vaporizers or hot spots for a considerable length of time at full load that the temperature of the vaporizer rises to such an extent as to cause a breaking down of the fuel and results in loss of power. The present invention has for its object to permit a reduction in the temperature of the vaporizer at will in the interest of efficient operation of the engine. To this end a portion of the fluid is diverted from the pump and directed into contact with the walls of the vaporizer. A further object of the invention is to replenish the cooling medium in the water jacket and radiator of the internal combustion engine, the volume of which is obviously diminished during an extended operation. To this end fluid from the pump may also be diverted to the circulatory system of the cooling system for the engine. A further object of the invention is to provide for the cooling of the vaporizer and the replenishing of the circulatory system by devices which are applicable to motors of standard design without involving material change in either the engine or the fire equipment. These and other objects of the invention will be more apparent from the following description of the accompanying drawing which shows, somewhat schematically, an internal combustion engine and water circulatory cooling system therefor and a fire pump to be driven by the engine, a preferred embodiment of the vaporized temperature control and the means for replenishing the water in the circulatory system being illustrated in detail.

The figure shows an elevation of the invention, partly in section.

In the drawing a fire pump is indicated in general at a and has a fluid inlet a' and outlet a^2 . Pump a is driven in any convenient manner from the internal combustion engine indicated in general at b . This engine is normally cooled by a water circulatory system comprising the water jacket b' from which cooling medium is conducted

by a pipe b^2 from a pump b^3 , which draws the water from a radiator c to which it flows through the pipe b^4 from the top of the water jacket b' . From a carburetor d the gaseous fuel is conducted to the respective cylinders by the intake manifold e and the hot exhaust gases are removed from the cylinders by the exhaust manifold f . A vaporizer or hot spot e' is formed in the walls of the intake manifold immediately above the carburetor by surrounding the walls of the intake manifold by a jacket f' communicating with the exhaust manifold f , a portion of the exhaust gases passing from the exhaust manifold downwardly in the direction indicated by the arrows into contact with the portion indicated at e' from whence the hot gases are withdrawn in the direction of the arrows back into the manifold f .

So much of the construction described may be termed standard equipment for automotive fire apparatus. After the engine has been running for an appreciable length of time the hot spot becomes so highly heated as to have a deleterious effect upon the gaseous fuel and it becomes necessary to reduce the temperature of the hot spot to an effective one. To this end water from the fire pump is introduced in the exhaust manifold jacket f' adjacent the hot spot e' . A pipe of smaller diameter g communicating at its one end with the outlet a^2 of the fire pump conducts a small quantity of water to the interior of the jacket f' . This pipe may be controlled by a valve g' in order that the operator of the engine may introduce the cold water as the need arises and control the temperature of the vaporizer by the quantity of fluid admitted. Introduction of a minimum quantity of cold water into the heating jacket f' reduces the temperature of the exhaust gases therein and in turn is vaporized and passes out through the exhaust manifold f .

After the engine has been running a considerable time the water in the cooling system, is depleted through leakage, etc. and a further aspect of the present invention contemplates means for replenishing the water in the circulatory system. To this end the pipe g is continued as at g^2 and leads into the pipe b^2 of the water cooling system of the engine. Water passage g^2 is controlled as by a manually operable valve

*g*³ and also in the line *g*² there may be inserted a check valve *g*⁴ to prevent the return flow of the fluid.

It will thus be seen that a convenient and practical means is provided for introducing cold fluid adjacent the vaporizer in order to maintain the temperature thereof at a predetermined point and means are also provided for replenishing the fluid in the cooling system of the engine, both said means being applicable to the prime mover and fire apparatus of standard design.

Various modifications may be made in the particular arrangement of parts and manner of vaporizing the fluid and no limitation is intended by the foregoing description or

illustration except as indicated in the accompanying claim.

What I claim is:

The combination with an internal combustion engine having a vaporizer surrounding a portion of an intake manifold, said vaporizer communicating with the exhaust manifold of the engine, and a fluid pump independent of the circulatory system of the engine, of a conduit to conduct fluid from the pump outlet to the vaporizer, and manually operable means to control the flow of fluid through said conduit. 20 25

This specification signed this 10th day of August, A. D. 1925.

GOTTFRIED WIRRER.
